Attorney.

UNITED STATES PATENT OFFICE.

JACOB MOE, OF TRONDHJEM, NORWAY.

ROTATING GRATE FOR AUTOMATIC STOKING.

1,342,026.

Specification of Letters Patent. Patented June 1, 1920.

Application filed February 28, 1920. Serial No. 362,133.

To all whom it may concern:

Be it known that I, JACOB MOE, a subject of the King of Norway, residing at Trondhjem, Norway, have invented certain new and useful Improvements in Rotating Grates for Automatic Stoking; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention has for its object a grate for automatic stoking, and according to the invention the grate comprises two circular disks with air slots rotating about axes perpendicular to the plane of the grate.

20 Further the invention comprises in combination with said rotating disks an oscillating arm adapted to move coal, slag and cinders from one part of the grate to another.

25 On the drawing:

Figure 1 is a vertical section and

Fig. 2 is horizontal section through a firebox provided with the present stoking device.

30 Fig. 3 is a cross section on line III—III on Fig. 2.

The grate according to the present invention comprises two circular disks 1 provided with air slots and rotatably mounted in the stationary grate. Said disks 1 are provided on their underside with toothed-wheels 2 engaged by pinions 3 on shaft 4, which can be rotated from the outside by hand or mechanically.

40 When the coals have been placed on a certain part of the front grate disk, they will be carried around with said disk during their combustion, while fresh coals are supplied to the front part of the disk.

45 During their movements the coals are en-

gaged by arm 5, which carries the same wholly or partly on to the rear grate disk, where the combustion is continued. The partially consumed coal, slag and cinders can be pushed by means of arm 5 back to 50 the front disk, so that the fuel is spread in an even layer over the whole grate surface. Arm 5 can be oscillated both ways by means of screw segment 6 engaged by screw 7, which is rotated from outside. Furthermore arm 5 may be moved vertically by means of arm 8 on shaft 9, which may also be operated from the outside. The free end of arm 8 engages the lower end of the rod 10 extending downwardly from the shaft of 60 arm 5, which is slidably connected with the said screw segment 6.

The adjustment of arm 5 in a vertical direction has for its object to regulate the thickness of the coal layer.

Claims:

1. In an automatic stoking grate having a substantially plane surface, the combination with two rotating grate disks of an arm mounted to oscillate in a plane parallel to 70 the grate surface and adapted to distribute coal, slag and cinders over the surface of the grate.

2. In an automatic stoking grate having a substantially plane surface, the combination 75 with two rotating grate disks, of an arm mounted to oscillate in a plane parallel to the grate surface and adapted to distribute coal, slag and cinders over the surface of the grate, the said rotating arm being adjustable vertically relatively to the surface of 80 the grate.

In testimony that I claim the foregoing as my invention, I have signed my name in presence of two subscribing witnesses.

JACOB MOE.
